UNITED STATES PATENT OFFICE.

GIDEON SUNDBACK, OF MEADVILLE, PENNSYLVANIA, ASSIGNOR TO HOOKLESS
FASTENER COMPANY, A CORPORATION OF PENNSYLVANIA.

SEPARABLE FASTENER.

1,243,458.

Specification of Letters Patent. Patented Oct. 16, 1917.

Application filed April 6, 1915. Serial No. 19,474.

To all whom it may concern:

Be it known that I, GIDEON SUNDBACK, a subject of the King of Sweden, residing at Meadville, in the county of Crawford and State of Pennsylvania, have invented certain new and useful Improvements in Separable Fasteners, of which the following is a full, clear, and exact specification.

This invention relates to separable fasteners, and has particular reference to that type of fastener for garments and other purposes, where two flexible stringers carrying similar members are locked and unlocked by a sliding cam device mounted on both members, the locking being effected by movement in one direction and unlocking by an opposite movement.

The objects of the present invention are to decrease the weight and bulk, to increase the flexibility, and to insure certainty of locking. A further object of the invention is to simplify and improve the cam sliding device.

According to the present invention, the stringers are alike, as in some prior types of this fastener, preferably consisting as herein shown of a fabric tape provided with a beaded or corded edge, upon which the hooks and eyes forming locking members are clamped. The locking members consist of contractible jaw portions which are clamped upon the tape and projecting locking portions of transversely elongated conical shape, so that the outside of one member nests within the recess of an adjoining member when in locked relation. The invention particularly resides in the shape and configuration of the locking members to provide an adequate opening for the locking movement, so that liability of catching is avoided, and guiding the projecting part smoothly and easily into the locking recess. Thereby, a snug fit is obtained and at the same time ample provision is made for movement of one member relatively to the other without disengaging when the fastener is flexed transversely or longitudinally.

In the accompanying drawings,

Figure 1 is a perspective view of an enlarged scale of a fastener embodying the invention;

Fig. 2 is a detail view showing the manner of locking and unlocking;

Fig. 3 is a cross section on the line 3—3 of Fig. 1;

Fig. 4 is a detail view of one of the locking members showing the recess;

Fig. 5 is a cross section thereof on the line 5—5 of Fig. 4;

Fig. 6 is a detail view of one of the stringers;

Fig. 7 is a cross section thereof;

Fig. 8 is a cross section of the slider, and

Fig. 9 is an enlarged detail of the locking members.

1—1 represents stringers which preferably will be made of woven tape having sewed thereto on opposite sides braided or twisted cords 2—2 to form a beaded edge. The cords preferred are twisted, and are sewed oppositely on each tape, so that the back twist of one tending to twist or pucker the tape, neutralizes that of the other. This construction enables twisted cords to be used instead of braided cords I have also employed, at a considerable saving in expense. By this construction of stringer composed of a tape having oppositely attached braided or twisted cords, the tape is not cut by the interlocking members behind the cords. This has happened and been a source of trouble and expense where a single cord has been inclosed or woven within the tape.

In manufacturing these stringers having a cord sewed on each edge, the cords are fed slower than the tape so as to be shorter, forming a "wavy" stringer. When the jaws are clamped thereon, this shorter edge elongates so as to almost equal the back edge of the stringer. A contraction of the stringer takes place when it is sewed by machine to the garment, so I prefer to make the cord considerably shorter than the stringer, as thereby a flat placket will be obtained. Also the stringers lie flat without either puckering or twisting.

3 represents the line of stitching as employed in the preferred construction. Each of these stringers may be secured together at one end by connecting members 4 having jaws similar to those of the locking members, and will have at the opposite end a stop member 5 also having similar jaws. These stop members 5 avoid unnecessary or clumsy projections, and do not increase the thickness of the fastener. 6 represents the sliding cam operating device, which consists of doubled stamped sides 7 each having a V-shaped channel, with their sides sep-

arated to permit passage of the tape portion of the stringers 1. 8 represents a cap having a point to fit between the diverging channels, and secured to the slider by a rivet 14. This cap also stiffens and braces the sides 7, and does not increase the thickness. 15 is a ring in which may be placed a pulling tape or bow 16. The stampings 7 may be integral and doubled over as shown, or they may be separate, in either event a rigid structure being provided when the cap 8 is applied thereto and the rivet 14 set.

Fig. 4 represents one of the hook or eye locking members, which consists of jaws 17-17 having a base portion 9 which is stamped or otherwise formed to provide an external hook or locking projection 10 and an eye member internal recess 11. These members, as well as the locking members 4 and the stop members 5 are stamped out of flat metal, and the flat jaws 17, 17 of these several locking, stop, and connecting members are spread apart as shown in dotted lines in Fig. 4 so as to pass over the corded edges 2 of the stringers. Then the jaws are set by a punch or other suitable means, the jaws thereby becoming firmly clamped to the stringers by the compression of the corded edges 2. This will be seen in Fig. 3, 30 where the corded edges have been distorted by the setting of the locking members thereon so as to completely fill the elongated slot in the locking members, and the jaws 17, 17 engaging firmly on the tape immediately behind the corded edges. This elongated slot enables the fastener to be thinner, and also lengthens the grip of the jaws on the stringers against pivoting up and down, without affecting the flexibility through the slider. 40 Practical success in a fastener of this character is largely dependent upon proper construction of the locking members. Not only must these members remain engaged when the fastener is flexed transversely or 45 one stringer moved longitudinally relatively to the other, but the locking members must guide smoothly into and out of each other without liability of jamming on the slider or on each other, and must always lock without objectionable looseness. These objects 50 are all obtained in the fastener of this invention, wherein not only are the locking members for both stringers alike, but they lock easily and surely without jamming and 55 yet provide the necessary flexibility. The members 10 are provided with opposite inclined guiding surfaces 18, 21, and 20, 20, the surfaces 21 being somewhat steeper, and rounded at the corners so as to fit in the 60 sockets 11 shown in Fig. 4. The upper surfaces of the locking projections are slightly rounded as shown at 24, and the projections and sockets are also elongated transversely as shown in Figs. 4 and 5. Also the under 65 surface is set at an angle to the surface of

the jaws 17, as seen in Figs. 1, 2, and 4, so as to form a cam surface 22 between the front edge of the socket 11 and the sharp edge 19, over which the rounded heads 24 may slide in locking and unlocking. The 70 angle of the guiding surface 18 conforms to the curve of the slider, and this surface, in conjunction with the sharp edge 19, causes the adjacent members on the opposite stringers to ride one on the other, and guide each other, into proper locking engagement. Thereby catching is eliminated, and by reason of the members guiding each other into locking engagement, the radius of the slider channel can be increased. This is of advantage 80 when the fastener is used on stiff garments such as corsets. The projections and sockets fit closely, and thus render the distance between the jaws independent of their thickness, which enables proper locking to 85 be secured with jaw members thinner than the projections, and consequently more separated on the stringers. Greater spacing of the jaw members increases the flexibility, but without the elongated and conical shaped 90 projections and recesses herein shown, this increased flexibility would enable the members to be easily disengaged by transverse bending.

By the present invention, an improved 95 fastener has been produced which is much more simple and cheap to manufacture than others heretofore invented, because both stringers as well as the respective members thereon, are alike, and the members themselves 100 can all be made by simple die operations from flat material. The only assembling operations are those required to attach the members to the tapes. The finishing of the locking members such as smoothing or tumbling is very simple, because all 105 are alike and the dies can be so designed as not to require much subsequent finishing of these members.

Having thus described my invention, I 110 declare that what I claim as new and desire to secure by Letters Patent, is:—

1. In a fastener, an interlocking member having a transversely rounded recess on one side, and a transversely rounded projection 115 on the opposite side extending from edge to edge of said member.
2. In a fastener, an interlocking member having a transversely elongated recess on one side, and a transversely elongated projection on the opposite side extending from edge to edge of said member.
3. In a fastener, an interlocking member having a rounded recess on one side, and a rounded projection on the opposite side continuous with the outer edge of said member.
4. In a fastener, an interlocking member having at one end a rounded recess on one side, and a rounded projection on the opposite side, the recessed side having a guiding 130

surface beyond the recess, and said projection having an inclined end forming an edge with said guiding surface.

5. In a fastener, an interlocking member having at one end a transversely elongated rounded recess on one side, and a transversely elongated rounded projection on the opposite side, the recessed side having a guiding surface beyond the recess, and said projection having an inclined end forming an edge with said guiding surface.

6. In a fastener, a member adapted for attachment to a stringer having a projecting end and a supporting end, the latter comprising compressible jaws separated by an elongated slot.

7. In a fastener, a stringer for carrying connecting members comprising a tape, and cords attached thereto on opposite sides along one edge.

8. In a fastener, a stringer for carrying connecting members comprising a tape, and oppositely twisted cords attached thereto on opposite sides along one edge.

9. In a fastener, a stringer for carrying connecting members comprising a tape, and cords sewed thereto on opposite sides along one edge.

10. In a fastener, a stringer for carrying connecting members comprising a tape, and oppositely twisted cords sewed thereto on opposite sides along one edge.

11. In a fastener, a fabric stringer having a corded edge for carrying connecting members, and having its opposite edge adapted for attachment to a device to be opened and closed, said corded edge being shorter than the attaching edge.

12. In a fastener, a stringer for carrying

connecting members comprising a tape, and oppositely twisted cords sewed thereto on opposite sides along one edge, the cords when attached being shorter than the other edge of the tape.

13. In a fastener of the class described, a fabric stringer, a flat body secured to the stringer and having an interlocking portion extending beyond the edge of the stringer, the body having an elongated slotted portion to receive the stringer and flat faced jaws at the end of said slotted portion projecting toward each other.

14. In a fastener, a fabric stringer having a thickened inner edge for receiving compressible interlocking members, and an attaching outer edge, said outer edge being longer than the inner edge.

15. In a fastener, an interlocking member having at one end a transverse recess on one face and a corresponding projection opposite said recess having a continuous surface extending between the edges of said member, said member having attaching means at the other end comprising jaws separated by an elongated slot.

16. In a fastener having a fabric stringer, a connecting member comprising a body having compressible separated clamping jaws at each end.

17. In a fastener having a fabric stringer, a U-shaped stop member having separated clamping jaws at each end.

In testimony whereof I affix my signature, in presence of two witnesses.

GIDEON SUNDBACK.
